US0D1015798S

(12) **United States Design Patent** (10) Patent No.: **US D1,015,798 S**
(45) Date of Patent: ** Feb. 27, 2024

(54) **FOOD PREPARATION DEVICE**

- (71) Applicant: **SharkNinja Operating LLC**, Needham, MA (US)
- (72) Inventors: **Joshua D. Anthony**, North Billerica, MA (US); **Dan Kestenbaum**, Brookline, MA (US); **Gary V. Palladino**, Somerville, MA (US)
- (73) Assignee: **SharkNinja Operating LLC**, Needham, MA (US)

(**) Term: **15 Years**

(21) Appl. No.: **29/888,471**

(22) Filed: **Mar. 31, 2023**

Related U.S. Application Data

- (62) Division of application No. 29/694,045, filed on Jun. 6, 2019, now Pat. No. Des. 982,375.

CLAIM

The ornamental design for a food preparation device, as shown and described.

DESCRIPTION

FIG. 1 is a perspective view of a food preparation device, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines are shown for the purpose of illustrating parts of the article that form no part of the claimed design.

1 Claim, 7 Drawing Sheets
